(57) **CLAIM**

The ornamental design for a bone fusion/fixation device, as shown and described.

DESCRIPTION

FIG. 1 is a front, top isometric view of a bone fusion/fixation device;

FIG. 2 is a rear, bottom isometric view of a bone fusion/fixation device;

FIG. 3 is a top view of a bone fusion/fixation device;

FIG. 4 is a bottom view of a bone fusion/fixation device;

FIG. 5 is a left-side view of a bone fusion/fixation device;

FIG. 6 is a right-side view of a bone fusion/fixation device;

FIG. 7 is a rear view of a bone fusion/fixation device; and,

FIG. 8 is a front of a bone fusion/fixation device.

Any shading and cross-hatching are not features of the design but are utilized to illustrate the surface contours of the bone fusion/fixation device design in the drawings.
